DESIGN FOR A HEAD UNIT FOR A MILKING MACHINE

Elmer B. Thompson and George A. Estel, Jr., Des Moines, Iowa, assignors, by mesne assignments, to Globe Milker, Inc., Des Moines, Iowa, a corporation of Illinois

Application February 15, 1945, Serial No. 117,979

Term of patent 14 years

(Cl. D23—1)

To all whom it may concern:

Be it known that we, Elmer B. Thompson and George A. Estel, Jr., citizens of the United States and residents of Des Moines, in the county of Polk and State of Iowa, have invented a new, original, and ornamental Design for a Head Unit for a Milking Machine, of which the following is a specification, reference being had to the accompanying drawing, forming part thereof, in which:

Fig. 1 is a front elevational view of a head unit for a milking machine showing our new design;

Fig. 2 is a top plan view;
Fig. 3 is a rear elevational view;
Fig. 4 is a bottom plan view;
Fig. 5 is a side elevational view looking toward the right in Fig. 1; and
Fig. 6 is a side elevational view looking toward the left in Fig. 1.

We claim:

The ornamental design for a head unit for a milking machine, substantially as shown.
